CLAIM

The ornamental design for a fruit bowl, as shown and described.

DESCRIPTION

FIG. 1 is a perspective view of the first embodiment of a fruit bowl showing our new design;

FIG. 2 is a rear view thereof.

FIG. 3 is a front view thereof.

FIG. 4 is a left side view thereof, a right side view being a mirror image.

FIG. 5 is a top view thereof.

FIG. 6 is a bottom view thereof.

FIG. 7 is a perspective view of the second embodiment of a fruit bowl;

FIG. 8 is a rear view thereof, a front view being the same as the rear view.

FIG. 9 is a top view thereof; and,

FIG. 10 is a bottom view thereof.

The broken lines in the drawings depict portions of the fruit bowl that form no part of the claimed design.
